UNITED STATES PATENT OFFICE.

ARCHIBALD G. SHAVER, OF CHICAGO, ILLINOIS, ASSIGNOR TO CASALE SAFETY DEVICE COMPANY, OF NEW YORK, N. Y., A CORPORATION OF NEW YORK.

SHOE.

1,383,865.

Specification of Letters Patent.

Patented July 5, 1921.

Application filed April 25, 1919, Serial No. 292,546. Renewed December 6, 1920. Serial No. 428,771.

To all whom it may concern:

Be it known that I, ARCHIBALD G. SHAVER, a citizen of the United States, residing at Chicago, in the county of Cook and State 5 of Illinois, have invented certain new and useful Improvements in Shoes, of which the following is a specification, reference being had therein to the accompanying drawing.

This invention relates to improvements 10 in a ramp engaging shoe, especially designed for use in conjunction with the vehicle carried circuits as set forth in my two co-pending applications, filed even date herewith, Serial Nos. 292,545 and 292,548.

15 In designing a shoe it is desirable to so construct it that the desired pressure is exerted thereon to hold it downwardly so that when yieldingly engaging the ramp at any speed, the electrical contacts controlled 20 thereby will be operated in a positive and effective manner.

A further object of this invention is the provision of a shoe connected to the air brake system and held downwardly and so 25 housed and constructed that should any of the shoe be broken off the air brake system will be vented to produce a stop condition.

A still further object of this invention is the provision of a shoe so housed as to be 30 protected from the elements and so constructed as to be readily attached to any part of the locomotive or motor vehicle desired, the same being provided with a removable ramp engaging portion so this worn part 35 may be removed at will without necessitating the changing of the other mechanism.

A still further object of this invention is the provision of a shoe held down by pneumatic force and which in its lowermost position holds the circuits closed but which 40 when moved to its highermost position and is jammed, will produce a danger condition, opening the circuit to set the brakes.

In the accompanying drawings:

45 Figure 1 is a view in elevation of the complete shoe.

Fig. 2 is a similar view thereof with the front casing removed and parts of the mechanism shown in section.

50 Fig. 3 is a section taken on line 3-3 of Fig. 1.

Referring to the drawings, the numeral 5 designates the casing of the present shoe, which is provided with a removable cover 6

for closing the chamber 7. Mounted in the 55 chamber 7 is a fixed hollow member 8, the upper end of which is in communication through a pipe 9 with the air brake system. In the lower end of the member 8 is a stuffing box 10 so that the hollow plunger 11 60 connected by the threaded engaging and locking nut 12 to the vertical and movable shank 13 of the vertical slidable shoe 14 may be properly connected and normally held downwardly by air pressure from the 65 system.

The shoulder 15 limits the downward movement of the shoe while the chamber 16 thereof is in communication with the air 70 brake system full length so that the breakage of the shoe at any point will vent the system and thus bring the train to a halt, so the reason may be ascertained. The lower end of the shoe 14 is provided with a socket 17 for the removable fastening of the wear 75 receiving plate or member 18, which is held in place by means of the bolts 19. By this means the plate 18 may be renewed when desired.

80 Detachably connected to the tubular member 11, within the chamber 7, is a clamp bracket 20 which carries the removable knife contacts 21 and 22 for engagement with the various pairs of contacts 23 and 24 and the oppositely disposed contacts 25 85 and 26, such contacts as shown in Fig. 2 being arranged so as to be supported upon the blocks 27 and 28 of insulation, mounted in the chamber 7.

The number of contacts are here shown 90 merely to indicate how the present shoe may be connected for controlling the circuits, but any number of contacts may be employed as may be found desirable.

What I claim as new is:

95 1. A shoe for electrical train control systems, including a support, a stationary plunger casing carried thereby and adapted to receive air from an air brake system, a vertical slidable hollow plunger having the 100 upper end mounted therein, a ramp engaging member carried upon the lower end thereof, said member being provided with an air chamber throughout the length thereof, the plunger and ramp engaging member 105 being held downwardly yieldingly by the air pressure and so that any breakage of the ramp engaging member will cause a leakage

of the air from the air brake system, and electrical contacts carried by the slideable member intermediate of the ends thereof.

2. A shoe for electrical train control systems, including a support having a chamber therein, a cylinder having one end for the connection with the air brake system mounted within the chamber, a hollow member sealed at its lower end and having its upper end in communication with and slideably mounted in said cylinder, the same being adapted to be yieldingly held downwardly by air pressure and the lower end of the latter being exterior of the support and adapted to engage a ramp, and coöperative circuit controlling means mounted in the chamber and connected to the hollow member.

3. A shoe mechanism, including a support having a chamber open at one side and having an opening through the lower end, a cover for the chamber, a cylinder having a stuffing box at one end and means at the other end for receiving air from an air brake system mounted in the chamber, a tubular piston slideable in the cylinder and mounted within the chamber, a ramp engaging member having a chamber extending from one end and terminating within the lower end, the upper end being connected to the lower end of the tubular member and movable therewith, said ramp engaging member being mounted for sliding movement in the opening of the support and held downwardly by air pressure, and means carried by the upper end thereof for limiting the downward movement of the ramp engaging member.

4. A shoe mechanism including a support, an air supplied chamber carried thereby, a tubular plunger mounted in said chamber for vertical movement, said plunger being sealed at its lower end, and carrying the shoe, a fixed electrical contact carried by the tubular member, and oppositely disposed electrical contacts carried by the support for coöperating with the movable contact member, said contact members being in electrical engagement when the shoe is in its lowermost position and being out of engagement

should the shoe be held in uppermost or abnormal position.

5. A shoe of the character described including a main casing having a hollow abutment leading from the lower end thereof, a plunger casing mounted within the main casing adjacent the upper portion thereof and in alinement with the hollow abutment, a tubular plunger mounted within the plunger casing for sliding movement, a ramp engaging member connected to the lower end and carried by the plunger and provided with a sealed chamber therein in communication with the plunger, the air pressure being disposed to hold the ramp engaged member and the plunger in downward position, and coöperative circuit making means carried by the plunger and mounted within the main casing, the circuit making means being in operable relation when the ramp engaging member is held downwardly and being disconnected when the ramp engaging member is in its uppermost position and jammed.

6. A shoe for electrical train control systems including a boxing having a ramp engaging member guiding portion in the lower end thereof, a ramp engaging member mounted for sliding movement in the latter and having a chamber leading from the upper end and terminating adjacent the lower end thereof, a plunger casing mounted in the boxing adjacent the upper end thereof, a tubular plunger for this member slideably mounted in the casing and its lower end detachably connected to the upper end of the ramp engaging member and providing a communicating means for the supply of air to the chamber of the ramp engaging member, the air acting to hold the ramp engaging member downwardly, an arm attached to the plunger, a contact member carried by the arm and insulated therefrom, a plurality of contacts mounted in the boxing and disposed to be engaged by the contact member of the arm, said latter contact member being out of engagement therewith when the plunger is in extreme upper position.

In testimony whereof I affix my signature.

ARCHIBALD G. SHAVER.
